PACKAGING TRAY FOR TOMATOES OR THE LIKE

Henry S. Levkoff, Great Neck, N.Y. (% Standard Fold-ing Trays Corp., 85th St. and 24th Ave., Jackson Heights 69, N.Y.)

Filed June 24, 1960, Ser. No. 61,108

Term of patent 14 years

(Cl. D58—12.6)

FIG. 1

FIG. 2

FIG. 3

FIG. 4

FIGURE 1 is a perspective view of a packaging tray for tomatoes or the like embodying my new design; FIGURE 2 is a plan view thereof;

FIGURE 3 is a side elevation thereof, and FIGURE 4 is an end elevation thereof.

I claim:

The ornamental design for a packaging tray for tomatoes or the like, as shown.
